E. Rhodes,

Spoke Lathe.

Patented Nov. 11. 1830.

New York

Nov 11, 1830

As per Acknowledgment of the Inventor, I do now and do hereby grant and acknowledge that of the same
invention and description in the word of the said Oliver Rhodes himself of his improved
invention to be filed.

To all to whom these presents shall come. To wit know that Oliver Rhodes
of the town of King'sbury in the County of Washington and State of New York
have invented a new and useful improvement in the Cutter for shaping
various articles of irregular form according to a pattern and that the follow-
ing is a full and exact description of the construction and operation of the
said improvement. That species of cutter to which this improvement is
applicable has been in use for a number of years past for the shaping of bars,
stocks and other articles of irregular structure according to the pattern of the
article to be formed. The general principle of its operation is well understood
and will therefore require but a brief description.

Two pieces of wood to be shaped and the pattern are both placed
at a suitable distance from each other in a frame capable of vibratory motion. They
have each a slow vibratory motion exactly like that produced by a suitable pinion at one
end of each as the pattern revolves it is made to come in contact with a ^{the edge of} smooth cast iron
which will cause the frame to vibrate backward and forward according to various
regularities in the pattern. The stock to be shaped at the same time comes in contact with
a wheel which rotates with great rapidity to whose circumference is attached numer-
ous cutters to operate on the wood. These two wheels are attached to the same frame &
constantly retain the same relation to each other. The frame which sustains them
is made to move slowly from one end of the stock to the other so that every part is
operated upon and brought to the shape of the pattern.

My improvement consists in using one or more cutters alone in the place of cut-
ters having a wheel. When one drawing used it is fixed upon an arbor and the cutting
wheeling and will form by little at only that on regulating its proportion lateral and
longitudinal to the thickness of the stock that of it need not move so fast
as to prevent the cutter from cutting any other. When the shape of the article to be formed
is such as to make it necessary to cut through long pieces of wood, it is

but to have two examinations upon the same day. The reason may be that the small amount of time available is that the first examination being of the hands, before the man is mounting it. What is claimed is the application of a curved or circular edge to the hand described, either of the purpose of shaping saw blades, trapping spikes, or other articles which may be shaped therein, especially Lest and Hat hooks. Dated 4th September 22, 1931.
